UNITED STATES PATENT OFFICE.

GEORGE L. GUILLIAMS, OF KANSAS CITY, MISSOURI.

DESIGN FOR A PASTRY-STAMP.

SPECIFICATION forming part of Design No. 29,470, dated October 11, 1898.

Application filed August 18, 1898. Serial No. 688,939. Term of patent 7 years.

To all whom it may concern:

Be it known that I, GEORGE L. GUILLIAMS, a citizen of the United States, residing at Kansas City, in the county of Jackson and State 5 of Missouri, have invented and produced a new and useful Design for a Pastry-Stamp, of which the following is a specification.

This invention is a new and useful design for a device for marking pies, the essential 10 features of the design residing in the peculiar shape and ornamentation of the device hereinafter fully described.

In the drawings forming part of this specification, Figure 1 is a view showing three 15 faces of the device. Fig. 2 is a perspective view showing three other faces of the device, and Fig. 3 is a face view showing one of the faces exhibited in Fig. 1.

Referring to the drawings, A indicates a 20 cubical body.

B is a cameo representation of a portion of an apple or a peach; C, a similar representation of raspberries; D, a similar representation of cherries, and E a representation of gooseberries. F represents a portion of a 25 peach.

A pastry-stamp constructed in accordance with the above-described design fulfils all the objects for which it is intended.

Having thus fully described my invention, 30 what I claim as new, and desire to secure by Letters Patent of the United States, is—

The design for a pastry-stamp, substantially as shown and described.

GEORGE L. GUILLIAMS.
